UNITED STATES PATENT OFFICE.

WILLIAM J. CAMERON, OF CHICAGO, ILLINOIS.

DESIGN FOR A LAMP.

57,206.

Specification for Design.

Patented Mar. 8, 1921.

Application filed April 28, 1919. Serial No. 293,359. Term of patent 14 years.

To all whom it may concern:

Be it known that I, WILLIAM J. CAMERON, a citizen of the United States, residing at Chicago, in the county of Cook and State of Illinois, have invented a new, original, and ornamental Design for a Lamp, as shown in the accompanying drawings.

In the drawings:

Figure 1 is a side elevation of my design for lamp.

Fig. 2 is a front view thereof, and

Fig. 3 is a rear view thereof.

What I claim is:—

The ornamental design for a lamp, as shown.

In testimony whereof I have hereunto set my hand at Chicago, Illinois, the 24th day of April, 1919.

WILLIAM J. CAMERON.
